UNITED STATES PATENT OFFICE

102,063

DESIGN FOR AN ANDIRON

Avery L. Norman, Dobson, N. C.

Application December 16, 1935, Serial No. 60,116

Term of patent 7 years

To all whom it may concern:

Be it known that I, Avery L. Norman, a citizen of the United States, residing at Dobson, in the county of Surry and State of North Carolina, have invented a new, original, and ornamental Design for an Andiron, of which the following is a specification, reference being had to the accompanying drawing, forming part thereof.

The essential characteristics of my design reside in the forwardly projecting feet with upwardly extending ribs extending therefrom along the side plates of the andiron, the projecting pairs of lugs on the upper bar, and the circular-shaped shelves overlying rearwardly extending members of the device.

I claim:—

The ornamental design for an andiron, as shown and described.

AVERY L. NORMAN.
